UNITED STATES PATENT OFFICE

JOHN B. OLSON, OF FORT ATKINSON, WISCONSIN, ASSIGNEE, BY MESNE ASSIGNMENTS, TO JAMES MANUFACTURING COMPANY, OF FORT ATKINSON, WISCONSIN, A CORPORATION OF WISCONSIN

FRAME FOR CATTLE STALLS

Application filed May 22, 1925. Serial No. 32,073.

My invention relates to improvements in frames for cattle stalls.

Objects of my invention are to provide a stall frame composed of standard units or members which can be adjustably connected to conform to the requirements for stalls of differing widths; to provide means whereby the stanchion supporting members of a stall frame may be constructed in units having 10 posts uniformly spaced from each other at a standard or standardized distance, whereby any one familiar with the standardized spacing of said posts may construct a stable and provide anchorage for such posts in concrete or in any other material without reference to the width of the stalls or the desired spacing between adjacent stanchion supporting units or pairs of posts and subsequently adjust the other members of the stall frame to 15 conform to such spacing; to provide means whereby standardized elements or members of stall frames may be kept in stock by dealers and sold to any one whose stable will permit of the anchorage of the stanchion supporting units, without any reference whatever to the length of the stable or the width 20 of the stalls.

In the drawings:

Figure 1 is a front elevation of a stall frame embodying my invention.

Figure 2 is a side elevation of one of the stalls, showing one member of the upper frame rod in cross section.

Figure 3 is a detail view, illustrating the 35 clamping connections of the stall frame unit posts with the upper horizontal bars of adjacent units and the intermediate adjustable connecting bar and partition member, one clamping member of each pair being removed 40 and a portion of the partition clamping member being partially broken away.

Like parts are identified by the same reference characters throughout the several views.

Each stanchion supporting unit comprises 45 two frame posts 5 and 6 connected at their upper ends by a tubular member 7 and clamping couplings 8. The clamping couplings are T-couplings with downwardly extending 50 portions of each pair adapted to engage the

associated vertical post, and one end of the horizontally extending portion adapted to engage the end portion of the tubular bar 7, preferably by means of an inwardly projecting arcuate flange 9 at or near the one end 55 of the horizontally extending portion of each coupling member. The other end of this horizontally extending portion of each coupling member is provided with a similar arcuate flange 10 which is formed to fit a rod or 60 tube 11 of sufficiently smaller diameter than the rod or bar 7 to allow it to be telescopingly 65 adjusted within said rod or bar 7 before clamping the coupling members thereto by means of the bolts 12, 12' and 13. Each of the posts 5 and 6 is provided at its lower end with a set of clamping members 14 which constitute a foot piece for the post and are adapted to be connected with a sill or beam 15 by means of clamping bolts 16, the nuts being 70 turned downwardly upon base flanges 17, as clearly illustrated in the drawings.

Any one informed as to the standard width of the stanchion supporting units, i. e., the distance between posts 5 and 6 of these units, 75 may provide properly spaced anchoring bolts 16 and couple the stanchion supporting units to the sill or beam 15 with the telescopingly adjustable rods 11 loosely in place. After the stanchion supporting units have been attached to the floor or beam 15 the rods 11 may be properly adjusted with their end portions telescoped at substantially equal distances 80 within the tubular rod members 7, after which the nuts 12' clampingly engage the arcuate 85 flanges 10 with the associated end portions of the rod 11. The nuts on the clamping bolts 12 may have previously been turned up to clamping position to bind the arcuate flanges 9 on the rod members 7. Where slight 90 errors occur in the spacing of the bolts 16 a variation will be permitted in the distance between the posts 5 and 6 of any stanchion supporting frame equal to the distance between the flanges 9 and 10 of the coupling 95 members, inasmuch as it is only necessary that the arcuate flanges 9 should embrace the associated rod member 7. But a much greater variation in spacing is permissible between adjacent stanchion supporting units because 100

the rods 11 are of sufficient length so that ordinarily they will extend into the associated tubes 7 for a considerable distance.

After the stanchion supporting units have been secured in position and connected with the spacing rods 11 as above described, the stall partition members may be attached to the rods 11 at any desired point between adjacent coupling members 8. In the construction shown each stall partition comprises a continuous rod bent to form a supporting post 20, a horizontally extending partition bar 21, and an oblique connecting bar 22. The upper end of the latter is secured to the associated spacing rod 11 by clamping members 24 similar in construction to the clamping members 8. However, the clamping members 24 will not require arcuate gripping flanges of differing size, and in fact the use of gripping flanges similar to either of the flanges 9 or 10 is not necessary for these couplings. The shanks or portions of the clamping members 24 which embrace the portion 22 of the partition will be made of sufficient length to allow for any desired variation in the distance between the post 20 and the line of posts 5 and 6. The couplings 8 may, of course, be used, if desired, inasmuch as the pairs of coupling members are spaced apart sufficiently to enable them to conform to a cylindrical surface with substantially the same efficiency that they can be conformed to and made to grip to cylindrical surfaces of differing diameter.

It will be obvious from the foregoing description that the width of the stalls will be determined by the extent to which the rods 11 are telescoped within the rods 7 when the installation is completed. The relative adjustment of the coupling members 8 upon the rod members 7 is not material so far as the width of the stall is concerned, and in fact the nuts on the clamping bolts 12 may, if desired, be turned to clamping position at the factory and the stanchion supporting frame units shipped as permanently organized units to the dealer or user, subject only to possible re-adjustment if the floor or sill bolts 16 are found to be misplaced to any extent.

The stanchions 25 may be secured to the frame bar members 7 and to the sill 15 in any convenient manner. They will preferably be connected to the members 7 by the clamping members 27 and to the floor or sill by a foot plate 28 and chains 29. These parts, however, form no part of the invention herein claimed.

If desired, one or both of each pair of clamping members 8 may be provided with an inwardly projecting stud 30 adapted to be received within a socket or hole 31 in the associated frame bar 7, whereby a more rigid connection between the posts 5 and 6 and the associated member 7 will be obtained and rotation of the members 7 prevented. Where

these interlocking projections are used, variations in the spacing of the posts 5 and 6 will not be permitted without elongating the sockets which receive such projections or providing a plurality of sockets for each projection.

I claim:

1. In a stall frame, the combination with posts and stall partitions, of a horizontally extending frame bar composed of members longitudinally adjustable upon each other, means for securing the stall posts and partitions to the alternate members, and means for securing stanchions to the intermediate members, whereby said longitudinally adjustable members may be utilized for stalls of differing widths.

2. In a stall frame, an upper frame bar comprising a series of stanchion supporting members, a series of longitudinally adjustable connecting members and sets of posts clamping engageable with the stanchion supporting members and stall partitions clamping engageable with said connecting members.

3. In a stall frame having an upper horizontally extending frame bar formed in sections longitudinally adjustable upon each other, the combination therewith of pairs of substantially uniformly spaced posts engageable with some of said sections, and stall partitions engageable with other sections, adjustably connectible to the first mentioned sections.

4. In a stall frame having an upper horizontally extending frame bar formed in sections longitudinally adjustable upon each other, each alternate section being of a length less than the width of a stall, the combination therewith of pairs of substantially uniformly spaced posts engageable with some of said sections, and stall partitions engageable with other sections, adjustably connectible to the first mentioned sections, each stall partition member being formed to extend obliquely, downwardly and rearwardly from the intermediate section which it engages to the partitioning portion thereof.

5. The combination with a stall frame having a series of relatively fixed members, including stall posts and partition members, the positions of which are determined by fixed floor anchorages, of a frame bar for connecting said relatively fixed members, said frame bar being formed in sections adjustable upon each other, clamps connecting the respective stall posts to alternate sections and other clamps each connecting one of the intermediate sections of said frame bar to one of the partitions.

6. In a stall frame, a set of horizontally extending stanchion supporting frame members, a set of intermediate frame members of smaller diameter telescopingly adjustable with reference to the first mentioned frame

members and post engaging reducer—couplings adapted to rigidly secure said members together in a desired position of relative adjustment.

5 7. In a stall frame, the combination with a series of posts, of an upper frame bar composed of a series of tubular rod-like members, intermediate members of smaller diameter having their ends telescopingly engaged in the tubular members, and connecting devices for securing said members to the respective posts, said connecting devices being adapted to clampingly engage the posts, the tubular members, and the intermediate 10 members to secure all of said members rigidly in position, with the frame bar members adjusted upon each other in accordance with the spacing of the posts.

8. The combination with a plurality of 20 stall frames, said frames each comprising a pair of spaced uprights and a horizontal connecting member at the tops of said uprights, of horizontal spacing and aligning members intermediate said frames and in telescoping 25 relation with said connecting members, whereby said frames may be adjusted longitudinally of said spacing and aligning members.

9. The combination with a plurality of 30 stall frames, said frames each comprising a pair of spaced uprights and a horizontal connecting member at the tops of said uprights, of horizontal spacing and aligning members intermediate said frames and in telescoping 35 relation with said connecting members, whereby said frames may be adjusted longitudinally of said spacing and aligning members, and partition elements supported by said spacing and aligning members.

40 10. The combination with stall units each comprising a stanchion supporting frame bar, posts, and means for securing the bars and posts together in their respective units; of connecting members for connecting frame 45 bars of adjacent units in any one of a plurality of spaced positions between said units, said means being engageable with said members for securing the latter to said bars.

11. The combination with stall units each 50 comprising a stanchion supporting frame bar, posts, and means for securing the bars and posts together in their respective units; of connecting members for connecting frame bars or adjacent units in any one of a plurality of spaced positions between said units, said means being engageable with said members for securing the latter to said bars, stall partitions, and means for securing said partitions to said connecting members.

60 JOHN B. OLSON.
